(Cl. D59—2)

To all whom it may concern:

Be it known that we, Lula Jane Pyle and Maxine H. Schell, citizens of the United States, residing at Kansas City, in the county of Jackson and State of Missouri, have invented a new, original, and ornamental Design for a Combined Favor Holder and Place Card, of which the following is a specification, reference being had to the accompanying drawing, forming a part thereof.

Fig. 2 is a top plan view thereof.

Fig. 3 is an end elevational view thereof.

Fig. 4 is an elevational view of the opposite end thereof; and,

Fig. 5 is a rear elevational view.

We claim:

The ornamental design for a combined favor holder and place card, as shown.

LULA JANE PYLE.
MAXINE H. SCHELL.
